US00D812226S

(12) **United States Design Patent** (10) Patent No.: **US D812,226 S**
(45) Date of Patent: ** Mar. 6, 2018

(54) **HEART VALVE PROSTHESIS**

- (71) Applicant: **Medtronic CoreValve LLC**,
Minneapolis, MN (US)
- (72) Inventors: **Than Nguyen**, Placentia, CA (US);
Hung Nguyen, Garden Grove, CA
(US); **Mykim Nguyen**, Santa Ana, CA
(US); **Stanley Komatsu**, Laguna Hills,
CA (US); **Robert Michiels**, Laguna
Hills, CA (US)
- (73) Assignee: **Medtronic CoreValve LLC**,
Minneapolis, MN (US)
- (**) Term: **15 Years**
- (21) Appl. No.: **29/505,733**
- (22) Filed: **Jun. 19, 2015**

Woodhouse & Mills PLLC

CLAIM

The ornamental design for a heart valve prosthesis, as shown and described.

DESCRIPTION

FIG. 1 is a side view of a heart valve prosthesis showing our new design; and,

FIG. 2 is a top view thereof.

The broken lines in the Figures show portions of the heart valve prosthesis which form no part of the claimed design.
